UNITED STATES PATENT OFFICE.

HARRY W. SMITH, OF NORTH GRAFTON, MASSACHUSETTS, ASSIGNOR TO DRAPER COMPANY, OF HOPEDALE, MASSACHUSETTS, A CORPORATION OF MAINE.

WEFT-REPLENISHING LOOM.

No. 845,904.

Specification of Letters Patent.

Patented March 5, 1907.

Application filed September 12, 1901. Serial No. 75,136.

To all whom it may concern:

Be it known that I, HARRY W. SMITH, a citizen of the United States, and a resident of North Grafton, in the county of Worcester and State of Massachusetts, have invented an Improvement in Weft - Replenishing Looms, of which the following description, in connection with the accompanying drawings, is a specification, like letters on the drawings representing like parts.

This invention is an improvement on the class of looms described in United States Patent No. 665,559, dated January 8, 1901. In that patent a filling-carrier and a feeler have one a magnetic and the other a magnetized body, and that on the carrier is normally covered by the filling when there is a sufficient or working supply of filling present on the carrier; but when the filling approaches exhaustion to a predetermined amount the body on the carrier becomes uncovered by the filling, and the magnetic and magnetized bodies of the carrier and feeler then become coupled together as the lay moves toward the fell on the beat up, and on the return or backward movement of the lay the feeler is drawn into an abnormal position, which causes usual filling supplying or replenishing means to be actuated to put fresh filling into the shuttle. In the construction set forth by said patent it is necessary that the bobbin or filling-carrier be provided with a magnetic or magnetized body which is covered during the spinning or winding of the filling; but in some cases it is desirable to use a filling-carrier or bobbin in a filling-replenishing loom of the above character which may not be provided with a magnetic or magnetized body, and in other cases it is desirable to use in the shuttle mule-cops, which being wound upon paper tubes render it impossible to utilize a magnetic or magnetized body on the filling-carrier, as the tubes would entirely cover said body and prevent exposure thereof for cooperation with the body on the feeler when the filling had become nearly exhausted.

To enable any form or character of filling-carrier to be used in a filling-replenishing loom, I have provided a feeler and shuttle, the one with a magnetic and the other a magnetized body, and preferably mount upon the feeler, which is supported in a yielding manner, as set forth in said patent, a calibrating-gage, which in the working of the

loom enters the shuttle and contacts with the filling on the carrier, to thereby prevent contact and coöperation between the magnetic and magnetized bodies on the shuttle and feeler, respectively, while a sufficient or working supply of filling remains upon the filling-carrier. By the term "caliper" or "caliper-gage," which is simply used as a means of identification, I mean a device having a part that contacts with the filling on the carrier to determine from the quantity of filling on said carrier the time when the magnetic and magnetized bodies shall come into operative engagement. As the amount of filling on the carrier gradually becomes less during the working of the loom the feeler enters the shuttle farther and farther, filling-induced movement of the feeler, however, on the forward beat of the lay toward the fell preventing contact and coöperation of the exposed magnetic and magnetized bodies on the shuttle and feeler, respectively, until when the filling has been nearly exhausted or exhausted to a predetermined amount the said magnetic and magnetized bodies meet, and on the backward movement of the lay the feeler is carried into abnormal position, due to the magneto-motive coöperation or adhesion between the said magnetic and magnetized bodies, whereupon the filling replenishing or supplying mechanism is caused to be actuated to supply fresh filling to the shuttle.

My present invention is applicable for use in connection with any known form of filling replenishing or supplying means for effecting a change of filling, and as the magnetic and magnetized bodies are carried by the shuttle and feeler, respectively, and are at all times exposed, it is evident that any usual character of filling-carrier may be employed.

Figure 1 is a detail looking at the left-hand side of a loom, showing a sufficient portion of an ordinary loom with my improvements added to enable my invention to be understood, the shuttle, the filling-carrier therein, and one wall of the shuttle-box being represented in section. Fig. 2 is a top plan view of the left-hand end of the loom shown in Fig. 1. Fig. 3 is a detail showing the caliper-gage in contact with the filling. Fig. 4 shows the filling exhausted to a predetermined extent sufficiently to enable the feeler-magnet to contact with the magnetic

body of the shuttle, and Fig. 5 is a side view of the shuttle.

The loom-frame 2, the breast-beam 3, the lay 4, having at its ends suitable shuttle-boxes, one of which is slotted at its bottom for the discharge of the filling-carrier b^2 , supplied with filling b^{2x} , the binder 9, the filling-fork 13, carried by the slide 14, the knock-off lever 15, pivoted at 16 and moved by the slide 14 whenever the filling breaks to release the shipper-handle 17 from its usual holding-notch and stop the loom, the connecting-rods 18 for moving the lay, the self-threading shuttle A, the rock-shaft 21, having an upwardly-extending arm 22, the slide-bar f^2 , having pivoted upon its inner end an overbalanced lever f^3 to thereby keep its outer end nearest the breast-beam normally in an elevated position, as shown in the drawings, the lever f^3 but partially shown, it having its upper end forked and operated once for each pick by a suitable cam on the usual cam-shaft, the filling-changing means represented by the pusher h , shown in dotted lines mounted on a stud h' and deriving its movement from the rock-shaft 21 whenever the slide-bar f^2 is moved backwardly in its guide, are common to United States Patents No. 529,940, dated November 27, 1894, and No. 633,976, dated September 26, 1899, and said parts, being fully described in said patents need not be herein further specifically described. I will also state that the wire coil 31, connected with and in a suitable circuit preferably with a source of electric energy, such—for instance, as a dynamo—said coil surrounding and guiding a feeler b , making of it a magnet which is maintained in normal balanced position by said coil, as is well understood in the operation of solenoids, the arm 34, extended from the rock-shaft 35 and resting on the inner end of the feeler, and the arm 36 and finger 37, overlying the inner end of the overbalanced lever f , are and may be all as fully provided for in said Patent No. 665,559, and instead of the wire coil shown, which makes of the feeler a magnet, I may use the equivalent means shown in said patent to normally balance a permanent magnet.

I will now describe the particular novel features which constitute the invention to be hereinafter claimed. I have provided the side wall of the shuttle A at or near the usual hole b^4 therein for the feeler with a body, as b^5 , represented as a metal plate, and to coact with this body I employ a feeler, and the body on the shuttle and the body of the feeler are one of magnetic and the other of magnetized metal. Preferably the shuttle carries the magnetic body and the feeler is a magnet. I have connected adjustably to the inner end of the feeler b a calibrating-gage b' , the length of which may be adapted to the thickness of the filling b^{2x} , wound on the

paper or other cop-tube d^3 , upon which the filling was spun on a mule or other suitable spindle. The front wall 10 of the shuttle-box, held in place as at 10 x , is cut away to expose the body b^5 to the action of the magnetized feeler.

In the operation of the loom at every other movement of the lay toward the fell the shuttle-box opposite the magnetized feeler will contain a shuttle having filling, and as the lay approaches the fell the filling will strike the end of the calibrating-gage and push the magnetized feeler outwardly or to the right, viewing Fig. 1, under the arm 34, and as the lay moves backwardly from the fell the wire coil or other equivalent will restore the magnetized feeler to its normal position. So long as a proper amount of filling is present in the shuttle the arm 34 will be sustained by the feeler and the pusher h will not act. As the filling is unwound in weaving its diameter gradually decreases, letting the calibrating-gage enter farther into the shuttle, and finally when the filling is sufficiently exhausted or exhausted to a predetermined point the end of the feeler is permitted to contact (see Fig. 4) with the body b^5 of the shuttle, and as the lay is moved backwardly from the fell the body b^5 adhering to the magnetized feeler will draw the latter with it from under the arm 34, which done the rock-shaft 35 will immediately turn, due to the weight of the finger 37, causing said finger to depress the normally elevated inner end of the overbalanced lever f^3 , so that the fork at the upper end of the lever f^3 will engage said overbalanced lever and, carrying the slide-bar f^2 with it, will through the arm 22 turn the rock-shaft 21 and actuate, in accordance with the patents hereinbefore referred to, the pusher h to insert fresh filling into the shuttle, said shuttle being, it will be understood, then at that end of the lay immediately under the usual hopper containing the supply of filling-carriers.

Instead of actuating a pusher, such as hereinbefore referred to, to change the filling when the feeler-magnet is put into its abnormal position, as stated, said feeler-magnet may in its abnormal position be made to control the starting of filling-changing means such as provided for in United States Patents No. 600,490, March 8, 1898, or No. 661,752, November 13, 1900, wherein provision is made for changing a shuttle from which filling has been exhausted and supplying for it a shuttle containing a supply of filling properly threaded, the change being effected after the indication showing that the filling has been exhausted to a predetermined point by a change of position of shuttle-boxes as therein provided for.

By the term "body" as applied to the device attached to the shuttle I intend to cover a piece of metal of any shape adapted to be

coupled with the feeler, due to magnetic action.

By adjusting the caliper-gage b' on the feeler-magnet by means of a screw, as shown in Fig. 1, or otherwise great nicety of operation may be attained to adapt the loom to the requirements of the cop used.

I have described the body b' connected with the shuttle as of magnetic material and the feeler b as a magnet; but this invention would not be departed from should the body b' be made a magnet and the feeler b be of magnetic material, yet this would not produce as good results as in the first-described plan.

In the claims I shall refer to the shuttle as having a body, and shall refer to the feeler as also having a body, and either of these bodies may be of magnetized, the other being of magnetic, material. As shown, the shuttle is provided with an open top and bottom.

Having described my invention, what I claim, and desire to secure by Letters Patent, is—

25 1. In a loom, a shuttle adapted to contain a supply of filling, a feeler adapted to feel for the filling in the shuttle, the wall of the shuttle and the feeler being provided the one with a magnetic and the other with a magnetized body, and filling-replenishing means operable upon the movement of the feeler into abnormal position.

2. In a loom, a shuttle adapted to contain a supply of filling, a feeler adapted to feel for the filling in the shuttle, and yieldingly held in normal position, the exterior surface of the wall of the shuttle and the feeler being provided the one with a magnetic and the other with a magnetized body, and filling-replenishing means operable upon the movement of the feeler into abnormal position.

3. In a loom, a shuttle adapted to contain a supply of filling, a caliper-feeler yieldingly supported in normal position, one having an exposed magnetic and the other an exposed magnetized body, the body carried by the shuttle being on the wall thereof and filling replenishing or supplying means operable upon movement of the feeler into abnormal position due to the coöperation of the said exposed magnetic and magnetized bodies.

4. In a filling-replenishing loom, a shuttle adapted to contain a supply of filling, a caliper-feeler yieldingly supported upon the framework of the loom adjacent one end of the lay, said shuttle and feeler having at all times, the one an exposed magnetic and the other an exposed magnetized body and filling-replenishing means operable upon movement of the feeler into abnormal position due to the coöperation of the exposed magnetic and magnetized bodies.

5. In a loom provided with filling-replenishing mechanism, a shuttle adapted to con-

tain a supply of filling, means to control the operation of said mechanism, said means including a yieldingly-mounted caliper-feeler adapted to be moved by the filling in the shuttle, and two continually-exposed metallic bodies carried by the feeler and the wall of the shuttle respectively, one of said bodies being magnetic and the other magnetized, filling-induced movement of the feeler preventing magneto-motive coöperation of said metallic bodies until the filling becomes nearly exhausted, coöperation of said bodies being then permitted to effect movement of the feeler and operation of the said controlling means.

6. In a filling-replenishing loom, a shuttle to contain filling, and a feeler, said shuttle having an opening for the entrance of said feeler and one having a magnetic and the other a magnetized body, the body carried by the shuttle being on the wall thereof, a calibrating-gage carried by said feeler to determine by the exhaustion of the filling to a predetermined point when said magnetic and magnetized bodies shall be engaged to put said feeler in its abnormal position, and filling-supplying means operative after the feeler has been put into its abnormal position to supply fresh filling to the loom.

7. In a filling-replenishing loom, a shuttle to contain filling, and a feeler, one having a magnetic and the other a magnetized body, the body carried by the shuttle being on the wall thereof, an adjustable calibrating-gage carried by said feeler to determine by the exhaustion of the filling to a predetermined point when said magnetic and magnetized bodies shall be engaged to put said feeler, in its abnormal position, and filling-supplying means operative after the feeler has been put into its abnormal position to supply fresh filling to the loom.

8. In a filling-replenishing loom, a shuttle having a hole in its side, a filling-carrier in said shuttle, a magnetic body attached to said shuttle near said hole, a feeler-magnet having an attached calibrating-gage to meet the filling on said carrier and prevent the engagement of said feeler-magnet and said body until after the filling has been unwound to a predetermined extent at which time the calibrating-gage enters the shuttle far enough to permit the feeler-magnet to engage said magnetic body and be moved thereby into its abnormal position.

9. In a loom, a shuttle provided with a hole at one side, and a feeler, said shuttle and feeler having one a magnetic and the other a magnetized body, the body carried by the shuttle being on the wall thereof, a filling-carrier adapted to receive upon it a tube containing filling, a calibrating-gage connected with said feeler and capable of entering farther and farther into the shuttle as the filling is unwound from said tube, the feeler meet-

- ing the body connected with said shuttle when the filling has been exhausted from said tube to a predetermined extent and putting said feeler into its abnormal position, and filling-changing means set in operation by putting said feeler in its abnormal position to supply fresh filling to the shuttle. 45
10. A lay having a shuttle-box, a shuttle in said box containing filling, a feeler to contact with the filling, and means to cause the shuttle-body, prior to full exhaustion of the filling, to engage and move said feeler with it in the movement of the lay and shuttle away from the fell. 50
11. In a loom, a shuttle, and a movable feeler, one having a magnetic and the other a magnetized body, a filling-carrier, a lay to move said shuttle toward and from the fell, and means to sustain said feeler, the absence of the filling from the filling-carrier to a predetermined extent causing said magnetic and magnetized bodies to be coupled and move said feeler with the shuttle and lay as they move backwardly from the fell. 55
12. A loom-shuttle comprising a body having in one of its walls a hole, and a connected metallic plate connected to a wall of the shuttle on the exterior surface thereof to act as the armature for a magnet. 60
13. A loom-shuttle comprising a body open at its top and bottom and having spring-arms to embrace and hold frictionally the head of a filling-carrier, the side wall of said shuttle having a connected metallic plate 65 constituting the armature of a magnet.
14. In a loom, a lay having a shuttle-box; a shuttle provided with a metallic body attached to a wall thereof, a filling-carrier in said shuttle, a magnetized feeler, means to sustain said feeler, a gage adapted to meet the filling on said filling-carrier at a movement of the lay toward the fell and thereby 70 prevent the contact of said magnetized feeler with the metallic body of the shuttle, the absence of filling from the filling-carrier to a predetermined point permitting said magnetized feeler to be coupled with the metallic body of the shuttle and to be moved backwardly therewith when the lay completes its backward stroke from the fell. 75
15. In a loom, a shuttle, a feeler, one having a magnetic and the other a magnetized body, a filling-carrier in said shuttle, a lay having a shuttle-box to receive said shuttle, means to move said lay toward and from the fell, a gage controlled by said feeler and adapted to be struck by the filling and moved with the lay toward the fell, the exhaustion of the filling from the filling-carrier to a predetermined point enabling the gage to enter 80 the shuttle for a distance sufficient to couple said magnetic and magnetized bodies and effect the movement of said feeler backwardly with the lay away from the fell. 85
16. In a loom, a shuttle-box, and a shuttle, each provided with a hole, a feeler to contact with the filling in the shuttle, an armature and a magnet one of which is carried by the feeler and the other by the wall of the shuttle-body. 90
17. In a filling-replenishing loom, a lay having a shuttle-box open at one side, a shuttle coating with said box and provided with an opening at one side, and a metallic body attached to the side of the shuttle adjacent 95 said hole.
- In testimony whereof I have signed my name to this specification in the presence of two subscribing witnesses.

HARRY W. SMITH.
